UNITED STATES PATENT OFFICE.

ERIC A. HOLMGREN, OF LYNN, MASSACHUSETTS, ASSIGNOR TO UNITED SHOE MACHINERY CORPORATION, OF PATERSON, NEW JERSEY, A CORPORATION OF NEW JERSEY.

METHOD OF SHAPING SHOE-UPPER MATERIALS.

Application filed January 3, 1922. Serial No. 526,599.

To all whom it may concern:

Be it known that I, ERIC A. HOLMGREN, a citizen of the United States, residing at Lynn, in the county of Essex and State of Massachusetts, have invented certain Improvements in Methods of Shaping Shoe-Upper Materials, of which the following description, in connection with the accompanying drawings, is a specification, like reference characters on the drawings indicating like parts in the several figures.

This invention relates to the manufacture of boots and shoes, and particularly to the shaping of the upper materials. The invention is herein illustrated in its application to the shaping of the toes of welt shoe uppers, but it will be recognized that in many of its aspects the invention is not limited to the shaping of the toe portion of the upper materials nor to welt shoe work.

In the manufacture of welt and other types of shoes it is important that the shape imparted to the upper materials be substantially maintained until they are permanently secured to the insole. In welt shoe work, for example, where the marginal portion of the upper materials is shaped to conform substantially to the angle between the feather and the rib of the insole, it is important to guard against any substantial distortion of the angular shape prior to the inseam sewing operation. Where stiffening material is included in the toe end portion of upper materials to produce what is termed a box toe, the stiffening material, by reason of its adhesive properties and its comparative rigidity after hardening, assists in maintaining the shape imparted to the upper materials and in preventing undesirable separation between different layers of the materials, for example between the leather upper and the lining. In welt shoe work, however, it has usually been the practice to apply a wire binder about the toe end of the upper to assist further in maintaining the angular shape of the marginal portion of the upper materials until they are secured to the insole, although it has been proposed, as disclosed in United States Letters Patent No. 1,389,678, granted on September 6, 1921, upon an invention of R. F. McFeely, to rely upon the stiffening material to hold the welt shoe upper in shape without the use of

extraneous fastening means round the end of the toe.

In its application to a method which dispenses substantially with extraneous fastening means about the end of the upper, as illustrated by said prior patent, and in other relations, the present invention has for an object to afford better insurance than heretofore against distortion of the shape of upper materials in the interval between the upper shaping and upper securing operations. In its accomplishment of this and other objects, the invention provides for utilizing cementitious matter, for example adhesive material such as is usually incorporated in box toe stiffeners, in contact with one or more edge surfaces on the upper materials to assist in holding the materials in shape. In practicing the method of the invention in the manner herein illustrated openings are provided in the leather upper in locations where upper shaping pressure is applied, and in the application of such pressure the stiffening material lying between the leather upper and the lining is made to flow into these openings to serve by engagement with the walls or edges of the openings as holding means when the stiffening material has hardened and the upper shaping pressure has been relaxed. For shaping the toe end portion of welt shoe upper materials the openings may advantageously be formed, as herein illustrated, in that portion of the margin of the toe of the upper which is shaped to provide a flange substantially perpendicular to the plane of the insole. It will be evident that, with the openings formed in this location, the hardened stiffening material presents in each opening a projection extending from the body of the stiffener in parallel relation to the plane of the shoe bottom, which assists in holding the upstanding flange of the upper not only from springing outwardly but also from springing upwardly, and thus further insures that the desired angle between the upstanding flange and the portion of the upper which is shaped to lie upon the feather of the insole will be maintained until the upper is secured to the insole.

The novel method of the invention will now be more particularly described with reference to the accompanying drawings,

which illustrate one manner in which the invention may be practiced, and will be pointed out in the claims.

The invention is herein illustrated in its application to the molding of the toe end portion of upper materials before they are mounted on the last, but it will be recognized that in many of its useful aspects the invention is not limited to molding off the last.

In the drawings:

Fig. 1 shows the toe portion of assembled upper materials, with openings formed in the margin of the upper for the purposes of the present invention;

Fig. 2 illustrates the molding of the toe portion of the upper materials off the last to produce a molded toe adapted to be assembled with a welt shoe insole, and shows how the stiffening material is made to flow into the openings provided in the margin of the upper, and

Fig. 3 shows the molded toe portion of the upper assembled with an insole on a last with the upper materials held in molded shape by the stiffening material prior to the inseam sewing operation.

While the invention is not limited in respect to the character and the manner of treatment of the stiffening material, it is contemplated that for shaping the toe portion of upper materials the invention may be practiced by the use of any well-known type of box toe stiffener including in its composition material which is normally hard but is capable of being rendered more or less fluent and adhesive, as by the application of heat. The drawings show a stiffener 2 which in accordance with one well-known practice is secured by stitches between the leather upper 4 and the lining 6 of the shoe. The leather upper, as shown in Fig. 1, is provided along the margin of the toe portion with a plurality of openings or perforations 8 which may be formed at any convenient time in the preparation of the upper materials. While the invention is not limited in respect to the number or character of these openings, it will usually be preferable for the purposes in view to provide a plurality of openings about the toe end of the upper, as illustrated. The openings or perforations may advantageously be elongated in the direction of the length of the marginal edge of the upper, as shown, in order to increase the holding effect of the stiffening material without an undesirable increase in the extent of the openings widthwise of the margin of the upper. For the purposes of a welt shoe manufacture the openings will preferably be located in that portion of the margin of the upper which is to be shaped into an upstanding flange to lie against the rib of the insole and will preferably be located above the line of inseam stitches on the inverted shoe, so as to avoid any tendency to weaken the inseam.

While the invention, as above suggested, is not limited in utility to welt shoe work nor to molding the upper off the last, the drawings illustrate such a molding operation on welt shoe upper materials between an inner form *a* and end embracing wipers, one of which is shown at *b*, Fig. 2, the form having an edge recess substantially right angular in cross section to provide an upstanding shoulder *c* against which the margin of the upper materials is pressed by the wipers to produce an upstanding flange at right angles to a portion of the materials which is molded to lie upon the feather of the insole. It will be noted by reference to Fig. 2 that the openings in the upper are located in that portion of the margin of the upper which is subjected to molding pressure between the shoulder *c* on the form and the co-operating edge faces of the wipers and are above the apex of the angle between the upstanding flange and the portion of the upper which is to lie upon the feather of the insole. It will be understood that at the time of the molding operation the stiffener will be softened in any well-known manner, for example by the application of heat before the upper materials are mounted on the form, in order to render it pliable with the stiffening material in a soft and adhesive condition. As the marginal portion of the upper materials is subjected to pressure between the form and the wipers the stiffening material is forced by the pressure into the openings 8 in the upper, as illustrated in Fig. 2. It will be understood that if the upper were shaped on the last substantially the same result would be effected by the pressure upon the marginal portion of the upper materials between the wipers and the rib of the insole. After the upper has been thus shaped or molded, the pressure will be maintained until the stiffening material has become substantially hard, whereupon the pressure will be released, and if the upper is molded as illustrated in Fig. 2 it will then be removed from the form and assembled with an insole 10 on a last 12 in the manner illustrated in Fig. 3. It will be evident that as a result of the upper shaping operation above described the hardened stiffener has integral therewith in each of the openings 8 in the upper a projection 14 formed of stiffening material which adheres to the edges of the opening and serves in addition to the adherence of the stiffening material to the inner surface of the margin of the upper to prevent the upstanding margin from springing outwardly away from the lining. It will also be evident that by reason of the arrangement of the projections 14 on the stiffener they serve additionally to prevent the upstanding margin of the upper from springing upwardly

away from that portion of the stiffener and the lining which is shaped to lie upon the feather of the insole, and thus insure that the upper will lie closely in the angle between the feather and the rib of the insole at the time of the inseam sewing operation, as is obviously desirable for the best results in securing the welt and the upper materials to the insole. With the openings in the upper arranged as shown, the inseam stitches will pass through the upper below the openings.

While the utility and advantages of the invention are not dependent upon the character of the upper materials, it is contemplated that the invention will be particularly useful where the leather of the upper is of an oily character or where for this or any other reason the stiffening material may fail to adhere readily to the inner surface of the upper leather. Where such conditions are encountered, for example, in welt shoe manufacture, there is a tendency for the angularly shaped marginal portion of the leather to spring away from the stiffening material, with the result that the angle between the upstanding flange of the upper and the portion which is shaped to lie upon the feather of the insole may be widened more or less, making it difficult in the inseam sewing operation to secure the upper materials and the welt closely in the angle between the feather and the rib of the insole. By the use of the method of this invention the holding effect of the stiffening material is substantially increased, both by reason of the adherence of the material to the edges of the openings in the upper and also by the action of the outwardly extending projections of the stiffening material in holding the upstanding margin of the upper closely down in the angle defined by the upper shaping operation. It is contemplated that the additional insurance thus afforded against distortion of the shape of the upper materials will be a substantial advantage not only where the materials are to be relied upon to maintain the shape imparted to them until the upper fastening operation without the use of extraneous fastening means about the end of the upper, but also where such fastening means may be employed to supplement the action of the stiffening material in the interval between the upper shaping and upper fastening operations.

Having explained the nature of the invention and set forth fully how it may be practiced, what I claim as new and desire to secure by Letters Patent of the United States is:

1. That improvement in methods of shaping shoe upper materials including an upper and a lining and stiffening material which is capable of flowing under the application of pressure, which consists in providing a por-

tion of the upper materials which is to be subjected to upper shaping pressure with one or more openings to receive said stiffening material, and by the application of pressure for shaping the upper materials to the desired shoe contour causing the stiffening material to flow into said opening or openings to assist in holding the materials in shape.

2. That improvement in methods of shaping shoe upper materials including a leather upper and a lining and stiffening material between the upper and the lining, which consists in providing the marginal portion of the leather upper with one or more openings and by the application of pressure forcing the stiffening material into said opening or openings in the upper to assist in holding the upper in shape.

3. That improvement in methods of shaping an end portion of shoe upper materials including an upper and stiffening material which is capable of flowing under the application of pressure, which consists in forming at the marginal portion of the upper a plurality of openings in different locations about the end of the upper, and by the application of pressure causing the stiffening material to flow into said openings to assist in holding the upper materials in shape.

4. That improvement in methods of shaping an end portion of assembled shoe upper materials which consists in forming a plurality of openings along the margin of said materials, applying pressure to said materials to shape them over a form, and binding different layers of the materials together by cementitious matter between the layers and in contact with the edges of said openings while the materials are under the shaping pressure.

5. That improvement in methods of shaping an end portion of assembled shoe upper materials including an upper and stiffening material which is normally hard but adapted to be rendered fluent and adhesive, which consists in forming in the marginal portion of the upper a plurality of openings in different locations about the end of the upper, applying pressure to the upper materials while the stiffening material is in a fluent and adhesive condition to shape the materials over a form and to force the stiffening material into said openings, maintaining the shaping pressure until the stiffening material has substantially hardened, and thereafter removing said pressure and utilizing the stiffening material to hold the different upper materials in shape until they are secured to the insole.

6. That improvement in methods of shaping an end portion of shoe upper materials including a lining and a leather upper provided with an edge surface on its marginal portion and having between the upper and

the lining stiffening material which is capable of flowing under the application of pressure, which consists in applying shaping pressure to the upper materials and by the application of such pressure on the marginal portions of said materials causing the stiffening material to flow over said edge surface of the leather upper to assist in binding the marginal portions of the different materials together.

7. That improvement in methods of shaping the toe end portion of welt shoe upper materials including stiffening material which is capable of flowing under the application of pressure, which consists in forming in that portion of the margin of the upper materials which is to provide an upstanding welt attaching flange one or more openings to receive said stiffening material, and by the application of pressure forcing the stiffening material into said opening or openings to assist in holding the upper materials in shape.

8. That improvement in methods of shaping the toe end portion of welt shoe upper materials including stiffening material which is normally hard but adapted to be rendered fluent and adhesive, which consists in forming in a portion of the margin of the upper materials which is to provide an upstanding welt attaching flange a plurality of openings adapted to receive said stiffening material, applying shaping pressure to the upper materials while the stiffening material is in a fluent and adhesive condition and by pressure applied at the margin of the materials forcing the stiffening material into said openings, maintaining the pressure on the margin of the upper materials until the stiffening material has substantially hardened, and thereafter removing said pressure and utilizing the stiffening material to

bind the marginal portions of the different upper materials together in the shape acquired until they are secured to an insole.

45

9. That improvement in methods of shaping the toe portion of welt shoe upper materials including a leather upper and a lining and stiffening material between the upper and the lining, which consists in forming in the margin of the leather upper a plurality of openings in locations where the margin is to be shaped to provide an upstanding welt attaching flange, applying shaping pressure to the upper materials and by pressure at the margin of said materials forcing the stiffening material into said openings, and utilizing the stiffening material in said openings after said material has substantially hardened to assist in holding the marginal portion of the upper in the angular shape acquired in the application of the shaping pressure.

55

10. That improvement in methods of shaping the toe portion of welt shoe upper materials including stiffening material which is capable of flowing under the application of pressure, which consists in forming along that portion of the margin of the upper materials which is to provide an upstanding welt attaching flange and in locations spaced from the location of the welt attaching seam a plurality of openings adapted to receive the stiffening material, applying pressure to shape the upper materials, and by the application of pressure on the margin of the materials causing the stiffening material to flow into said openings to assist in maintaining the marginal portion of the materials in the angular shape acquired in the application of the upper shaping pressure.

65

In testimony whereof I have signed my name to this specification.

ERIC A. HOLMGREN.
